PROTECTIVE AND REFLECTIVE DEVICE

Gerald A. Besnah, 3633 N. 23rd St., Milwaukee, Wis.

Filed June 8, 1956, Ser. No. 590,255

7 Claims. (Cl. 128—372)

The subject invention is concerned with a protective and reflective device for a reclining individual and is particularly concerned with an enclosure that reflects light rays, keeps undesirable materials from the user and affords privacy.

Individuals interested in absorbing light rays, such as sun bathers or users of sun lamps generally enjoy this activity in a reclining position. In this position certain problems are presented, particularly where the individual involved is a sun bather on a sandy beach. The effect of the wind blowing across the sand or the ground may be irritating. Moreover, other users in the immediate area may kick sand or otherwise annoy the reclining individual. Accordingly, it is seen to be desirable to have a type of enclosure which affords some measure of privacy for the sun bather. When an enclosure is used in this fashion, as shown in the subject invention, the walls can then be so positioned as to beneficially increase the ordinary intensity of the light rays on the reclining individual.

This type of enclosure would generally be used by sun bathers at a beach or park, and it would be desirable to have an enclosure that can be collapsed into a compact, lightweight, portable unit.

Accordingly, it is an object of the present invention to provide a reflective device enclosing a reclining individual.

Another object of the subject invention is to provide a protective and reflective device that surrounds a reclining individual and beneficially increases the natural intensity of light rays falling on the individual.

A further object of the subject invention is to provide an outdoor protective and reflective device that includes ground contacting elements enabling the device to be set up on any type of a generally horizontal surface.

Still another object of the subject invention is to provide an outdoor protective and reflective device that includes associated portions allowing the walls of said device to be pitched relative to the supporting surface.

A further object of the subject invention is to provide an outdoor protective and reflective device that can be collapsed to form a compact, lightweight, portable unit.

Other objects will be apparent from the following description when read in connection with the drawings, in which:

Fig. 1 is an isometric view showing the protective and reflective device in the open position;

Fig. 2 is an elevation view of an intersection of the walls of the device showing the walls in partially pitched position;

Fig. 3 is a view similar to Fig. 2 showing the walls in the full pitched position;

Fig. 4 is an end view of the left side wall shown in Fig. 1 in various pitched positions with a ground contacting element attached thereto;

Fig. 5 is an enlarged isometric view of an embodiment of a ground contacting element;

2

Fig. 6 is an enlarged isometric view of another embodiment of a ground contacting element;

Fig. 7 is an isometric view, partly broken away, showing the protective and reflective device in partially folded position;

Fig. 8 is an isometric view showing the device in fully folded position; and

Fig. 9 is an isometric view showing the device in use on an elevated structure.

10 Referring to the drawings by characters of reference Fig. 1 illustrates a front wall 20 comprising a center bar 21 and a pair of front panels 22 and 23 associated with center bar 21 by hinges 24 and 26. Left side wall 27 is seen to comprise a plurality of side panels 28, 29, 30 and 31 with intersecting or pitching means 33 associating one end of side wall 27 with one end of front panel 22. Side wall 34 is similar to and corresponds with side wall 27 and comprises side panels 36, 37, 38 and 39, which are similar to and correspond with side panels 28, 29, 30 and 31. Intersecting or pitching means 41 is similar to and corresponds to pitching means 33 and associates one end of side wall 34 with front panel 23.

20 It should be understood that pitching means 41 operates in the same manner as pitching means 33, and accordingly, only the function of pitching means 33 which joins side wall 27 to front wall 20 will be described, it being understood that pitching means 41 functions in the same manner in joining side wall 34 to front wall 20.

25 It will be noticed that the side panels of side walls 27 and 34 gradually diminish in height toward their free ends. End panels 28 and 36 are seen to be the same height as front panels 22 and 23 while intermediate panels 29, 30, 37 and 38 decrease in height and free end panels 31 and 39 are the smallest in height. The diminishment in height of the side walls is possible as the reclining individual's head will generally be positioned near the front wall 20 where the greatest height affords the most protection.

30 The walls of the protective device are preferably formed of aluminum to afford a high degree of reflection and lightness of weight, and the decrease in size of the intermediate and free end panels will decrease the weight and cost of the device. However, the invention is not to be considered to be limited to any particular relation of size between the panels or to panels made of aluminum as any light weight material, such as plastic or cloth, may be used for forming the panels. In the aluminum embodiment shown the edges are turned over, as indicated, for example, by edge 40 on panel 39 for easy, safe handling, smoothness, and strengthening of the panel.

35 Also, in the Fig. 1 embodiment it will be noted that free end panels 31 and 39 are connected to adjacent panels 30 and 38 by hinges 52 and 53, respectively, so that panels 31 and 39 can swing outwardly in a 180° arc and fold alongside panels 30 and 38. Hinges 54 and 55 connect intermediate panels 30 and 38 to adjacent intermediate panels 29 and 37, respectively, so that panels 30 and 38 can swing inwardly in a 180° arc and fold alongside panels 29 and 37.

40 Hinges 57 and 58 connect intermediate panels 29 and 37 to end panels 28 and 36, respectively, so that panels 29 and 37 can swing outwardly in a 180° arc and fold alongside panels 28 and 36. Hinges 59 and 60 connect end panels 28 and 36 to front panels 22 and 23, respectively, so that panels 28 and 36 can swing inwardly in a 90° arc and fold alongside panels 22 and 23. Thus, the reflective device is shortened by collapsing into a compact, portable unit.

45 Pitching or corner means 33 comprises a pair of triangular shaped corner portions 42 and 43 mounted at their lower ends on pivots 45 and 50, respectively, to lower corners of end panel 28 and front panel 22, respectively. As more clearly seen in Figs. 2 and 3 corner por-

tions 42 and 43 have elongated arcuate slots 44 and 46 formed in their upper sections. Threaded pins 47 and 48 are fixedly mounted in adjacent upper corners of panels 22 and 28 and adapted to project through and slidably fit in slots 44 and 46, respectively. Wing nuts 49 and 51 are threaded on pins 47 and 48 for locking the pins in any selected position along the slots.

A plurality of elements shown as ground contacting supports 62 may be attached by hinges 63 to side walls 27 and 34. Only one element is shown in Fig. 1 but more than one could be attached on each side wall if such support is desired. At the same time it should be emphasized that the protective device can be used without any supporting elements mounted on side walls 27 and 34. For example, on a sandy base, such as a beach, the side walls could be forced down into the sand thereby supporting themselves. However, supports 62 will be found helpful, particularly if a strong wind is blowing against the walls.

In the foot element 62 shown in Fig. 1 a foot member 64 is attached to hinge 63 and projects outwardly therefrom in operable position. A circular shaped foot pad 66 is fastened at the outer end of member 64 to give a larger supporting surface. A brace 67 is loosely connected at one end to the outer end of member 64 and angles upwardly toward wall 34 terminating at a hook 70 which can be selectively connected to any one of a plurality of loops 68 fastened in side wall 34. Due to the hinged connection 63 brace 67 can be detached from loop 68 and the element 62 folded flat against side wall 34.

Another embodiment showing a foot element appears in Fig. 5 where a hinge 69 is used in the same manner as in Fig. 1. Foot element 71 comprises a foot member 72 extending from hinge 69 with a brace member 73 hingedly connected at the outer end of foot member 72. A rail 74 is fastened to the outside of side wall 34 and includes a runner 76 slidably mounted therein and having a loop 77 for engagement with a hook 75 on the end of brace 73. A wing nut 78 is threadedly engaged with runner 76 and in contact with rail 74 so that tightening of wing nut 78 will lock runner 76 in any selected position along rail 74. Element 71 can also be folded flat along side wall 34 by loosening wing nut 78 and allowing runner 76 to move to the top of rail 74.

Still another embodiment showing a foot element appears in Fig. 6 where a sliding stake element 81 is used to penetrate the surface on which the protective device is placed. Stake element 81 comprises a shaft 82 having a point 83 at one end and an internally formed slot 84 at the other end. A threaded pin 86 is mounted in wall 27 to project either on the outside or inside of the wall and is illustrated in Fig. 6 as projecting on the inside of side wall 27. Pin 86 passes through slot 84 and has a wing nut 87 threaded thereon so that stake 81 can be selectively locked in any desired vertical position with respect to side wall 27.

The foot element embodiments 62 and 71 shown in Figs. 1 and 5 can be used on any surface although they may be particularly practical where the surface is difficult to penetrate, such as hard ground, stone or concrete. The embodiment 81 shown in Fig. 6 would be particularly useful in soft ground or sand to aid in supporting the protective device.

A screened enclosure 91 may be formed in each side wall 27 and 34, as shown in Fig. 1, to permit ventilation to pass through the side walls and over the individual reclining inside. If ventilation is not desired, this screened enclosure can be covered by flaps 92 mounted on hinges (not shown) on the inside of the side walls. When the enclosures 91 are open, flaps 92 are locked in upward open position by pivoted latches 93.

Another embodiment of the protective and reflective device is shown in Fig. 9 where it is used on an elevated structure shown as a cot 101 having crossed legs 102 and 103, and horizontal projecting parts 104. The same numbers are used in Fig. 9 to designate elements similar

to elements appearing in the embodiment shown in Fig. 1. Openings or cut out sections 106 are formed in end panels 28, 31, 36 and 39 so that the entire unit when placed on cot 101 will be supported on projections 104. 5 When the protective device is used on an elevated structure, as the illustrated cot 101, the device will be constructed of a size to conform to the shape of the cot where the cot will be of a type having the projecting horizontal portions 104.

When the protective and reflective device shown in Fig. 1 is in use, the walls may be pitched or maintained relatively perpendicular to the ground surface. When the walls are not pitched relative to the ground the intersecting or pitching means are only used to associate the front and side walls, but in this position some reflection or increased intensity of the light rays will be available. However, when the walls are pitched by using the pitching means, greater beneficial effect of the reflection of the light rays off the walls will be realized. To adjust the walls 20, 27 and 34 of the embodiment shown in Fig. 1 to a pitched position wing nuts 49 and 51 of pitching means 33 are loosened. Only the operation of pitching means 33 will be described, it being understood that pitching means 41 operates in the same manner. The walls 20 and 27 are then pitched out and pins 47 and 48 will slide in slots 44 and 46 to the desired position. A small degree of pitch may be established, such as shown in Fig. 2 or the maximum pitch utilized, as shown in Fig. 3, and the wing nuts 49 and 51 thereupon tightened to lock the walls in the desired pitched position. Foot elements, such as the preferred embodiment 71 shown in Fig. 5, are then adjusted by sliding runners 76 in rails 74 to the corresponding desired position where members 72 will be horizontal to the surface. Foot elements 71 are the preferred embodiment as the runners 76 can be selectively locked in an infinite number of positions whereas foot elements 62 shown in Fig. 1 are restricted in their various positions to the number of loops fastened to wall 34.

The pitched positions of the walls are more clearly shown by the dash dotted lines in Fig. 4 where side wall 27 is shown in approximately the same positions established by the corner pitching means 33 in Figs. 2 and 3.

When it is desired to fold up the protective device for easy portability, the foot elements 71, if they are being used, are first folded up alongside the walls 27 and 34, and the corner means 33 and 41 are placed in the un-pitched position shown in Fig. 1. Free end panels 31 and 39 are then folded outwardly on hinges 52 and 53, respectively, up against intermediate panels 30 and 38, respectively. The two sets of panels 30, 31 and 38, 39 are then folded inwardly on hinges 54 and 55, respectively, up against intermediate panels 29 and 37, respectively. The two sets of panels 29, 30, 31 and 37, 38, 39 are then folded outwardly on hinges 57 and 58, respectively, up against end panels 28 and 36, respectively. The two sets of panels 28, 29, 30, 31 and 36, 37, 38, 39 are then folded inwardly on hinges 59 and the hinges (not shown) on corner means 41, respectively, up against front panels 22 and 23, respectively. The two sets of panels 22, 28, 29, 30, 31 and 23, 36, 37, 38, 39 are then folded inwardly on hinges 24 and 25, respectively, about center bar 21 to form a compact portable unit, as shown in Fig. 8.

65 The direction of folding is clearly shown by the arrows in Fig. 7 where the device is illustrated in partly folded position. The completely folded unit appears in Fig. 8 where it will be noticed that a handle 131 is mounted on center bar 21 for ease in carrying. Fastening means 132 connects panels 22 and 23 to prevent the device from opening in closed position and comprises a loop 133, which may be leather, fastened to panel 22 and a hook 134 fastened to panel 23 to fit through and engage an opening in the end of loop 133. A plurality of fastening

means 132 can be used, if desired, spaced along end panels 22 and 23.

It is understood that the open shape of the protective device is not limited to the shape shown in Fig. 1. Various other combinations of folded panels can be used.

The particular embodiments of the invention illustrated and described are to be considered illustrative only. The present invention includes such other modifications and equivalents as may readily occur to those skilled in the art, within the scope of the appended claims.

It is claimed and desired to secure by Letters Patent:

1. A protective and reflective device constructed for placement on the ground comprising a plane surface reflective front wall having a predetermined length, a pair of side walls, each of said side walls being connected to hinged corner portions connecting said side walls and said front wall, said side walls extending outwardly from said front wall along the ground, said corner portions located at the intersection of said walls and having hinge connections, each of said portions having slots formed therein, and means mounted on said walls for selective engagement with said slots for determining the pitch of said walls relative to the ground, said walls being hinged in sections and arranged to collapse upon themselves to form a compact portable unit.

2. A protective and reflective device constructed for placement on the ground comprising a front wall having a predetermined length and positioned to form an angle with the ground, a pair of side walls, each of said side walls being connected at one end with an end of said front wall and extending outwardly therefrom along the ground, said side walls diminishing in height toward their free ends, corner portions located at the intersection of said walls, each of said portions comprising a pair of hinged together triangular shaped parts having an elongated slot formed therein, each of said parts pivotally mounted on one of said walls, holding means mounted on said walls and selectively engageable along said slots for determining variations in pitch of said walls relative to the ground, and elements associated with said walls and adapted to be placed in contact with the ground for maintaining said walls in said pitched position, said walls hinged in sections and adapted to collapse upon themselves to form a compact portable unit.

3. A protective and reflective device as set forth in claim 2 in which said elements comprise slotted stakes slidably mounted on said walls and fastening means associated with said walls being operable to maintain said walls in a selected vertical position with respect to said walls.

4. An outdoor protective and reflective device constructed for placement on the ground comprising a front wall having a predetermined length greater than its height and positioned to form an angle with the ground, a pair of side walls, each of said side walls associated at one end of said front wall and extending outwardly therefrom along the ground, said side wall diminishing in height toward their free ends, corner portions located at the intersections and pivotally mounted along the bottom edge of said walls with slots formed therein, holding means integral with said walls and slidably positioned in said slots for selective engagement therewith for determining variations in pitch of said walls relative to the ground, elements hingedly mounted on said walls and projecting outwardly therefrom along the ground, each of said elements having a member pivotally mounted on its free end and extending upwardly and adapted for selective

engagement along the outside of said walls to maintain said walls in one of said selected pitched positions, said walls, portions and elements hinged to be folded upon themselves to form a compact portable unit.

5. An outdoor protective and reflective device constructed for placement on the ground comprising a front wall having a predetermined length greater than its height and positioned to form an angle with the ground, said front wall including a center bar with a hinged front panel on either side, a pair of side walls, each of said side walls associated with one end of each of said hinged panels and including a plurality of hinged side panels diminishing in height toward their free ends, corner portions located at the intersections and pivotally mounted along the bottom edge of said walls with arced slots forming therein, holding means integral with said walls and slidably positioned in said slots for selective engagement therewith for determining variations in pitch of said walls relative to the ground, elements hingedly mounted on said walls and projecting outwardly therefrom along the ground, each of said elements having a member pivotally mounted on its outward free end and extending upwardly and inwardly for selective engagement along the outside of said walls to maintain said walls in one of said selected pitched positions, said hinged side panels foldable upon themselves onto each of said hinged front panels and said front panels foldable about said center bar to form a compact portable unit, a carrying handle mounted on said center bar and fastening means associated with the ends of said side panels to maintain said unit in folded position.

6. An outdoor protective and reflective device as set forth in claim 5 in which said walls are formed of light weight metal.

7. An outdoor protective and reflective device constructed for placement on the ground comprising a front wall having a predetermined length, a pair of side walls, each of said side walls being connected at one end to an end of said front wall and extending outwardly therefrom along the ground, corner portions located at the intersection of said walls and hingedly associated for 180° swinging movement of one relative to one other, each of said portions having a pair of hinged together triangular shaped parts having an elongated slot formed therein, each of said parts pivotally mounted on one of said walls, holding means mounted on said walls and selectively engageable along said slots for determining variations in pitch of said walls relative to the ground, and elements associated with said walls and adapted to be placed in contact with the ground for maintaining said walls in said pitched position, said walls hinged in sections and adapted to collapse to form a compact portable unit.
